APPARATUS FOR CHARGING FURNACES

Aimé Pierre Joseph François-Bongarçon,
Paris, FranceApplication May 22, 1935, Serial No. 22,896
In France June 6, 1934

7 Claims. (Cl. 214—36)

The present invention has for its object an improvement in the charging of blast furnaces, shaft furnaces and the like, in order to ensure a better distribution of the charges.

Usually, the drop of the materials charged, for example in a blast furnace, takes place around the cone closing the base of the throat, or of a truncated distributing cone located below.

These materials thus drop on to an annular zone and can only spread out on the charging plane of the blast furnace by tumbling. Now, the angle of repose varies in particular with the nature of the materials and their degree of division. The result is that the alternate layers of coke and of ore do not have a uniform thickness. Furthermore, a classification of the materials takes place according to their size. As the coke and the large pieces of ore roll on the slopes, they accumulate towards the centre and the periphery, whereas the fine ore remains in the zone of descent. The gases pass with greater difficulty in this vertical zone than in the rest of the section of the blast furnace. This gives rise to irregularities in the heating of the materials, an incomplete reduction of the oxides by the gases and an exaggerated consumption of coke.

According to the invention, these drawbacks are avoided by distributing the materials over the surface of charge, in concentric zones, forming by their juxtaposition, alternate layers of coke and of materials to be smelted which are practically horizontal, thereby avoiding tumbling. Furthermore, these concentric zones are supplied with coke and materials to be smelted in constant proportions, whereby the respective superposed layers of coke and of materials to be smelted offer a constant resistance to the passage of the gases in the whole of the section of the blast furnace.

The actual number of concentric zones in the plane of charge is not limited, but is chosen in each case to give the best results and taking into account the extent of the surface of charge.

The accompanying drawing illustrates, by way of example, one embodiment of a device for carrying out this method of charging, along three concentric zones, by means of a particular arrangement of the cone closing the throat (or of the truncated distributing cone).

Fig. 1 is a perspective view of the modified cone. Fig. 2 is the corresponding plan view.

Figs. 3, 4 and 5 are sections along III—III, IV—IV, and V—V, of the preceding figure.

Fig. 6 shows, on a smaller scale, the general arrangement of the modified throat.

Fig. 7 is a diagrammatic view of a modified arrangement of baffle plates, and

Fig. 8 is a diagrammatic view of a further modification of baffle plates.

The throat shown in Fig. 6 is applicable to blast furnaces charged by a fixed hopper. The conventional elements of the charging throat are found therein. However, the lower cone 1 of the hopper 1' is modified and has cut-out portions 2, 3 provided with partitions 4, 5 and 5'.

The portions of the cone corresponding to the non-cut-out surfaces are intended to pour a portion of the materials charged, on to the outer zone of charge. They are bordered by guides 7, limiting the spacing of the materials in their fall. The cut-out portions 2 and 3 are intended for supplying the two other zones, towards which the partitions 4 and 5, 5' guide the materials. The partition 4, which is fixed vertically or slightly inclined, opposite the cut-out portion 2, prevents the materials overflowing on to the outer zone and throws them back into the medial zone. The partition 5 forms, with the partitions 5', a chute which is inclined in an oblique direction with respect to the axis of the furnace and which directs towards the inner zone material entering the cut out portion 3. The partition 5 also extends towards the left so as to cause a spreading of the charge for the inner zone over a circumference of greater angular extent than the cut out 3 of the distributor cone. These arrangements are shown diagrammatically by Figs. 3, 4 and 5, in which has been illustrated at 8 the wall of the blast furnace, at 9 its axis. The cone is shown in full lines in its closed position and in dotted lines in its open position. a, b, c are the various zones of charge.

The full portions and the cut-out portions of the cone are arranged in pairs, symmetrically with respect to the axis of the cone. The full and cut-out portions are measured respectively by their angles at the center of the furnace which vary in size proportionally to the zones to be supplied. In the example chosen, the projections on a horizontal plane of the full portions take up an angle of 180° and those of the cut-out portions 2 and 3, respectively, 120 and 60°. In order to obtain in the three zones a, b, c, layers of materials of equal heights, the width of the zones is calculated as follows:

The portion fed by the full portions totalling 180° of the surface of the cone will receive $\frac{180}{360}$ or $\frac{1}{2}$ of the total charge. The portion fed by the smallest cut-out totalling 60° will receive $\frac{60}{360}$ or $\frac{1}{6}$ of the total charge. The 120° portion will re-

ceive the difference or $\frac{1}{3}$ or the total charge. To spread these amounts equally the cross-sectional area of the furnace is divided theoretically into three zones whose areas correspond to the charges to be received. Thus, taking the radius of the furnace to be unity its area is πr^2 or $\pi 1^2$ which equals π . Since $\frac{1}{2}$ of the charge falls in the outer zone, due to the 180° cone section feeding it, the area of this zone should be $\frac{1}{2}$ the total area or $\frac{1}{2}\pi$. The radius x of the circle dividing the outer zone from the central zones would then be found from the equation

$$\pi x^2 = \frac{\pi r^2}{2}$$

15 since $r=1$,

$$\pi x^2 = \frac{\pi}{2}$$

$$20 x^2 = \frac{1}{2}$$

$$x = \frac{1}{\sqrt{2}} = 0.707$$

25 Similarly, the radius y of the circle separating the central zones would be found from the equation

$$\pi y^2 = \frac{\pi r^2}{6}$$

30 Since the area of the innermost theoretical circle is $\frac{1}{6}$ of the total area, being fed by 60° of the distributor cone. Therefore, r^2 equalling

$$y^2 = 1/6$$

$$35 y = \frac{1}{\sqrt{6}} = 0.408$$

40 The radii of the circles separating the furnace cross section into three zones furnish a measure of the widths of the zones. The outer or largest zone has a width of $1 - 0.707$ or 0.293. The middle zone is $0.707 - 0.408$ or 0.299.

45 Having these figures of width available the distributor is provided with means associated with each charging region of the cone surface for directing its charge into the proper band or zone. The partition-guides 7 collect, over an angle of 60° of the outer zone, the materials which run out over the full portions of the cone. Similarly 50 the outlet opening of the chutes 5, 5' is such that said chutes pour the materials over 60° of the inner zone.

55 At each charge, the cone thus distributes between the various zones of the plane of charge portions of the material poured into the hopper, which portions are shown diagrammatically at a' , b' , c' . For the following charge, the cone is rotated through such an angle that the fresh supplies of materials are juxtaposed in each zone 60 with respect to the preceding ones. In the example chosen, said angle is 60° . After the cone has been rotated half a turn, all the zones are thus completely charged. For such a division of the cone and of the surface of charge, the quantities of materials falling into each zone are proportional to the surfaces of the said zones, and the heights of the layers of coke and of materials to be smelted are respectively equal in each zone.

70 By modifying the surfaces of the full and cut-out portions of the cone, while retaining the same zones of charge, or conversely, while retaining the surfaces of the full and cut-out portions, but modifying the width of the zones of descent, that is to say, by changing the slope and the length 75 of the surfaces and of the guides of the cone, a

fuller charge can be obtained in one or several zones with respect to the others.

However, since this increase of supply takes place both for the coke and for the materials to be smelted, the proportion between the coke and the materials is not modified, and the resistance of the charges to the passage of the gases remains constant for the various zones. This possibility enables a horizontal level to be retained in the charge of the materials, even if the descent 10 of such materials is more active for certain annular zones. This case occurs frequently in furnaces having a wide hearth, in which the combustion does not take place over the whole section of the plane of the tuyères, but only over an annular 15 zone; the more rapid descent vertically through this zone is compensated by a greater supply in the corresponding zone at the top of the blast furnace.

In order to enable the cone to be rotated, according to Fig. 6, its suspension rod 10 has been given a polygonal or equivalent section and on said rod has been mounted a worm wheel 11 which is fixed in position and in which the said rod can slide. Said wheel is driven by a worm 25 12. It is quite obvious, moreover, that an apparatus which is quite similar to and independent of the closure cone can be used in the event of it not being desired to rotate the closure cone. It is sufficient in this case to provide a cone 30 having cut-out portions and guides, located below the closure cone and actuated in an identical manner by a shaft passing inside the hollow rod effecting the opening and the closing of the cone of the throat.

The distributor cone 1 is suspended on the rod 10 which is rotatable through its worm wheel 11 as described. The rod 10 is supported against vertical movement by means of the thrust plate 15 which is carried on the frame 16 through 40 bearings 18. The frame 16 is supported by means of rods or the like 17 whereby it may be elevated or dropped. By reason of the sliding engagement of the section 19 of the shaft 10 in the worm gear 11 the cone 1 is made to follow the movements of the rod 17. A closure cone assembly 13 45 surmounts the distributor cone 1 and is connected to the frame 16 and rods 17 for movement therewith. The object of the cone 13 is to permit the free rotation of the distributor 1 without opening 50 the hopper 1' and the cone 13 is small enough so as not to overlap the portions of the distributor cone which separate the charge.

In Fig. 7 the partition 4 between the zones a and b is shown partly inclined for the purpose 55 of indicating a workable variation of the partition shown as vertical in Fig. 4.

Fig. 8 shows a further variation of the partition 4. Both Figs. 7 and 8 have modifications of the partition 4 which will serve to retain flowing 60 charging materials within the boundaries of the proper zone.

Of course, the invention is not limited to what is described and illustrated, but can give rise to modifications ensuing from the same principle 65 of distribution of the charges. This method of charging, specially described with respect to its use in blast furnaces, is applicable to any industrial apparatus having a vertical shaft and the satisfactory operation of which relies on a supply 70 in horizontal and regular layers of materials, as for example lime kilns, plaster kilns, or ore roasting furnaces, vertical carbonization furnaces etc.

I claim:

1. In a charging device for a shaft furnace, 75

- 5 a cone having peripheral portions cut out, said cone being of such a width as to place its periphery at a radial portion in the furnace just short of an outer circumferential charging zone, said 5 cut out portions being cut towards the apex of the cone to place the inner edge of the portion at a radial position in the furnace just short of a middle circumferential charging zone, a deflector placed below certain of said cut out portions in 10 a vertical position in the furnace between the outer and middle charging zones to direct a charge falling in such portions to the middle zone, and a deflector placed below the others of 15 said cut out portions in an oblique position in the furnace extending from the line between the outer and middle zones to a position approximately on the line between the middle and the inner 20 charging zones to direct a charge falling in such portions to the inner zone, the magnitudes of the 25 cut out and uncut portions of the cone measured by angles at the apex thereof being in direct proportion to the areas of segments in the zones 30 cut out by a single angle measured from the center of the furnace.

25 2. A device for charging a shaft furnace comprising a distributing cone with a diametrically opposed pair of uncut portions of 90° of the circumference of the cone each, a pair of diametrically opposed cut-out portions of 60° each, a pair 35 of diametrically opposed cut-out portions of 30° each, said 90° portions adapted to distribute a charge in the furnace near the wall thereof, a substantially vertical baffle on the cone beyond the end of the 60° portions to confine a charge 40 within a ring lying radially inside of the charge distributed by the 90° portions, and a downwardly and centrally sloping baffle on the cone beyond the end of the 30° cut-out portions to distribute a charge to the center of the furnace without overlapping the charge distributed by the 60° 45 portions.

45 3. A device for charging circular furnaces comprising below the feeding funnel a distributing cone the surface of which is divided up into two diametrically opposed solid portions measuring 90° each at the apex of the cone, two diametrically 50 opposed cut out portions of 60° each measured at the apex of the cone, and two diametrically opposed portions of 30° each measured at the apex of the cone, and means associated with each of 55 said portions for directing a charge flowing down the cone surface into three concentric zones of the furnace.

55 4. A device for charging circular furnaces comprising below the feeding funnel a distributing cone divided into two diametrically opposed solid portions of 90° each measured at the apex of the cone, two diametrically opposed cut out portions of 60° each measured at the apex of the cone, two diametrically opposed cut out portions of 30° each measured at the apex of the cone, said 60 solid sections of 90° each being designed to feed a circular zone adjacent the wall of the furnace, each of said 90° portions having a pair of vertical guides to cause material flowing on the cone sur-

65 face to drop within an angle of 60° measuring from the apex of the cone, whereby two diametrically opposed portions of the said zone are provided with a charge filling an angle measuring 60° from the center of the furnace at each charging operation.

65 5. A device for charging circular furnaces comprising below the feeding funnel a distributor cone the surface of which is divided into two diametrically opposed portions of 90° each measuring from the apex of the cone, two diametrically opposed portions of 60° each measuring from the apex of the cone, two diametrically opposed portions of 30° each measuring from the apex of the cone, means on said cone in the region of 10 said 90° portions for restricting a charge to fall within a zone in the furnace measuring 60° from the center, and means on said cone in the region of 15 said 30° portions for restricting a charge to fall within a zone in the furnace measuring 60° from the center.

10 6. A device for charging circular furnaces comprising below the feeding funnel a distributor cone the surface of which is divided into two diametrically opposed portions of 90° each measuring from the apex of the cone, two diametrically opposed portions of 60° each measuring from the apex of the cone, two diametrically opposed portions of 30° each measuring from the apex of the cone, means on said cone in the region of 20 said 90° portions for restricting a charge to fall within a zone in the furnace measuring 60° from the center, means on said cone in the region of 25 said 30° portions for restricting a charge to fall within a zone in the furnace measuring 60° from the center, said 60° portions and said 30° portions being cut away towards the apex of said cone, baffles on the cone in the region of said 60° portions to restrict a charge falling through said 30 cut out portions to an intermediate circular zone 35 in the furnace, and baffles on said cone adjacent said 30° portions for directing a charge falling through said portions to the center of the furnace, said 40 90° portions being solid and the charge from said portions feeding an outer circular zone in 45 said furnace.

45 7. A charging device of the character described comprising a distributor cone the surface of which is divided into feeding portions separated from one another and adapted to divide up a 50 charge flowing down said cone, said feeding portions being adapted to feed a number of concentric circular furnace zones, said portions being laid out on the surface of said cone along angles measured at the apex of said cone which angles 55 vary in magnitude in proportion to the areas of the zones cut by a single angle measured from the center of the furnace, and means associated with said feeding portions for directing the respective charges to cover areas of the respective 60 zones equal to the corresponding areas cut by said single angle.

AIMÉ PIERRE JOSEPH
FRANÇOIS-BONGARCON. 65
